DESIGN FOR A COSMETIC BOX OR THE LIKE

Richard O. Tillmann, Merrick, N. Y., assignor to American Can Company, New York, N. Y., a corporation of New Jersey

Application February 9, 1946, Serial No. 126,428

Term of patent 14 years

(Cl. D58—13)

To all whom it may concern:

Be it known that I, Richard O. Tillmann, a citizen of the United States of America, residing at Merrick, in the county of Nassau and State of New York, have invented a new, original, and ornamental Design for a Cosmetic Box or the like, of which the following is a specification, reference being had to the accompanying drawing, forming a part thereof.

Figure 1 is a perspective view of a cosmetic box or the like embodying my new design;

Fig. 2 is a side view thereof; and

Fig. 3 is a top plan view thereof.

I claim:

The ornamental design for a cosmetic box or the like, as shown.

RICHARD O. TILLMANN.
